SLIDER FOR INTERLOCKING FASTENERS

Frank MacWilliams, Philadelphia, Pa., assignor
to Samuel Seltzer, Philadelphia, Pa.

Application June 14, 1934, Serial No. 730,609

7 Claims. (Cl. 24—205)

This invention relates to slides for what are commercially known as interlocking fasteners, wherein metallic lugs along contiguous edging tapes are interengaged and disconnected through movement of the slides in opposite directions along the tapes; and it has reference to both the construction and assembling of such slides.

In the main, my invention is directed toward the provision of an improved interlocking slide whereof the component parts lend themselves readily to economic fabrication in quantity as punchings or die stampings from sheet metal; and which parts, by virtue of certain novel structural characteristics, and because of novel steps followed in assembling them, predetermine, with absolute accuracy, a neat, compact and ornamental product that can be relied upon for long service without causing excessive wear on the fastener elements or lugs.

Other objects and attendant advantages of this invention will be manifest from the following detailed description of the accompanying drawing, wherein Fig. I is an enlarged fragmentary view showing my novel slide in association with a conventional form of interlocking fastener.

Figs. II, III, IV and V are perspective views of the several die stamped sheet metal parts from which the slide is constructed; and,

Figs. VI, VII and VIII are views showing successive steps followed in assembling the slide.

With reference first to Fig. I of these illustrations, the numerals 10 and 11 designate the edging tapes to which the opposing interlocking lugs 12 and 13 are permanently secured in the well known manner; while the numeral 14 comprehensively designates the slider of my invention. It is to be understood that the slider 14 functions in exactly the same manner as ordinary sliders, i. e. to interengage and disconnect the interlocking lugs 12 and 13 incident to being moved longitudinally of the edging tapes 10 and 11. As already pointed out hereinbefore, the present improvements are more especially concerned with the formation and assembling of the die stamped sheet metal parts which enter into the construction of my novel slider, said parts being separately illustrated and identified respectively by the numerals 15, 16, 17 and 18 in Figs. II—VIII.

The parts 15 and 16 are identical in shape and size and constitute what may be conveniently termed the face components of the slider. As shown, the components 15 and 16 have a configuration resembling that of a shield with a flat back 19 that is convergent downwardly and which is bounded by concave side edges 20 with convex

top and bottom edges 22 and 21, said side edges being provided with flanges 23 in perpendicular relation to the back 19. Each face component 15, 16 is furthermore provided with a square notch 25 centrally of its top convexed edge 22 and a square aperture 24 medially of its back 19. The components 15 and 16 may be formed in a single operation, or they may be blanked, and the flanges 23 turned up by a separate upsetting operation if desired.

The part 17, which I will refer to hereinafter as the connecting component, has an irregular configuration with an elongate horizontal medial portion 26 and end extremities 27 and 28 which are inclined outwardly and upwardly from said medial portion at acute angles. At the juncture between the extremity 27 with the medial portion 26, the component 17 is well rounded as at 29 with provision of a semi-circular notch 30 at the crotch of the angle. Substantially at the center, the main portion 26 of the connecting component 17 has an upstanding tongue or projection 31 which is recessed in its top as at 32, and which, at one side, is separated from the semicircular notch 30 by an intervening notch 33. There is also a well defined notch 34 between the right side of the projection 31 and the sloping inner edge 35 of the extremity 28 of the connecting component 17. Adjacent their ends 36 and 37, the extremities 27 and 28 are respectively formed with inwardly-directed rectangular-section rivet projections 39 and 40.

The part 18 illustrated in Fig. V is perfectly flat and designed to serve as a pivoted finger grasp for the slider 14. As shown, the upper and lower portions 41 and 42 of the finger grasp 18 are divergent with respect to a narrower central waist portion 43, the upper portion 41 being bifurcated and the extremities 44 of the bifurcation formed respectively with inwardly-directed terminal pivot projections 45; while the lower portion 42 is provided with a circular aperture 46 at the center.

The slider 14 is assembled by first arranging the face components 15 and 16 with their broader ends uppermost and their side flanges 23 facing toward each other as in Fig. VI, then engaging their upper edge notches 25 respectively with the notches 33 and 34 of the connecting component, and then swinging them outward so that their apertures 24 receive the rivet projections 39 and 40 on the extremities 27 and 28 of the connecting component 17. With this accomplished the projections 39 and 40 are then peened or headed over as at 47 and 48 to permanently secure the face components 15 and 16

to the connecting component 17, whereupon the latter is bent to U-configuration to bring said face components into parallel relation as shown in Fig. VII with their inner sides abutting the 5 projection 31 of the connecting component 17 and with their top portions firmly clinched by incidental closing up of the notches 33 and 34 of said connecting component. It is to be particularly noted that the projection 31 of the 10 connecting component 17 accurately determines a definite interval between the curved edge flanges 23 respectively of the face components 15 and 16, so that the slide may move freely over the interlocking lugs 12 and 13 (Fig. I) on the edging tapes 10 and 11, with said flanges lapping the outer ends of said lugs. After bending of the connecting component 17 as just explained, the recess 32 in the upper end of the projection 31 is shaped, by means of a suitable tool, to semi- 15 circular configuration as shown in dotted lines at 49 in Fig. VII, for capacity to cooperate smoothly with the interlocking lugs 12 and 13. Finally, the finger grasp 18 is brought up as 20 shown in Fig. VIII and its extremities 44 pressed toward each other, as indicated in dotted lines, to engage the pivot lugs 45 with the eye 50 (Fig. VII) jointly formed by the outer side of the face component 15 and the notch 30 of the connecting component 17. 25

As a consequence of the described novel construction and assembling of the parts 15-18, it will be seen that there is afforded an interlocking slider which is neat, compact and ornamental in appearance, which is secure against the possibility of detachment or displacement of its component parts, and which can be relied upon for long service without occasioning excessive wear of the interlocking lugs.

Having thus described my invention, I claim:

- 40 1. A slider for interlocking fasteners comprising a pair of opposingly-disposed face components having inwardly-directed guide flanges, and a bifurcate connecting component embodying extremities for sustaining the side components and having notches at opposite sides of a spacer projection, within the crotch thereof, in which the transverse confronting edges of the side components are fixedly held by a clinch grip.
- 45 2. A slider for interlocking fasteners according to claim 1, wherein registering transverse edges of the face components are formed with notches for interlocking engagement with the crotch notches of the bifurcate connecting component.

3. A slider for interlocking fasteners according to claim 1 wherein the face components are permanently secured at a medial point to the extremities of the bifurcate connecting component.

4. A slider for interlocking fasteners according to claim 1 wherein square rivet projections on the extremities of the bifurcate connecting component pass through corresponding apertures in the face components, and said projections are peened over to permanently secure the face components to the connecting component.

5. A slider for interlocking fasteners according to claim 1 wherein the face components have central notches in their inner transverse edges for interlocking engagement with the crotch notches of the connecting component, and the extremities of the latter component have square rivet projections for peened fixture in correspondingly-configured apertures medially of the first mentioned components.

6. A slider for interlocking fasteners according to claim 1, including a finger grasp with a split loop pivotally engaged in an eye jointly provided by an inner edge notch in one of the connecting component extremities and the confronting portion of the attached face component.

7. A slider for interlocking fasteners comprising opposed shield-like face components each embodying transverse convex edges with intervening concave side flanges and a medially-located rectangular orifice, one of the convex edges of each said face component having a centrally located rectangular notch; a connecting component including a medial portion with relatively acute-angled extremities each of which has an inwardly-directed rectangular-section rivet projection proximate its outer end for peened fixture in a face component orifice, an upstanding spacer projection centrally of the connecting component inner medial portion defining with the angled extremities thereof clinch notches for reception of the face component edge notches when the connecting component extremities are inwardly-clinched into parallel relation, said spacer projection having its free end recessed at right angles to the plane of the spacer, a well rounded notch in one of the connecting component angled extremities inwardly of its rivet projection defining an eye with the confronting face component, and a finger grasp with a bifurcate portion whereof the extremities are pivotally engaged in the eye aforesaid.

FRANK MACWILLIAMS.
